UNITED STATES PATENT OFFICE.

HARLEN L. BEE, OF SALEM, WEST VIRGINIA.

DUST-COLLECTOR.

1,267,171.

Specification of Letters Patent. Patented May 21, 1918.

Application filed September 29, 1916. Serial No. 122,903.

To all whom it may concern:

Be it known that I, HARLEN L. BEE, a citizen of the United States, residing at Salem, in the county of Harrison and State 5 of West Virginia, have invented new and useful Improvements in Dust-Collectors, of which the following is a specification.

This invention is an improved dust collector for use in connection with a grinding machine such as is used by dentists, jewelers, and others, the object of the invention being to provide an improved machine of this character that is simple in construction, is compact, which can be readily manufactured at low cost and which has powerful suction and also serves to separate heavy dust, and other heavy particles from light dust.

The invention consists in the features of 20 construction, combination, and arrangement of devices, hereinafter fully described and claimed.

In the accompanying drawings:

Figure 1 is a perspective view of a dust 25 collector constructed and arranged in accordance with my invention and showing the same mounted on a jeweler's stand.

Fig. 2 is a sectional view of the dust collector, on a larger scale.

Fig. 3 is a detail sectional view at right angles to Fig. 2.

Fig. 4 is an elevation of a modified form 30 of my dust collector showing the same mounted on a dental table.

Fig. 5 is a detail longitudinal sectional view of the suction fan.

Fig. 6 is a transverse sectional view of the same.

Fig. 7 is an elevation of a modified form 40 of the suction fan.

Referring especially to the form of the invention shown in Figs. 1, 2, and 3, my improved dust collector comprises a pair of vertical tubes 1, 2, respectively provided at 45 their lower ends with detachable trap closures 4. The pipe 1 is provided on its inner side with a horizontally arranged arm 5. The tube 2 is provided on its inner side with a similar horizontal arm 6. A conduit 7 is detachably fitted in the arm 5 and is provided at its inner end with a down turned elbow 8 which is detachably fitted on the vertical arm 9 of a conduit 10. Said conduit 10 is detachably fitted at its outer end in the arm 6 and is connected at its inner end to the casing 11 of a revoluble suc-

tion fan 12. Said suction fan casing is secured to one side of the stand or other support 14 and is provided on its lower side with a discharge arm 15 to which a dust collecting bag 16 is attached, the said dust collecting bag hanging from the discharge arm of the fan casing. Hoods, 17, 18 which are arranged over the emery wheels or other grinding elements 19, 20, are provided at 50 their lower sides with arms 21, 22 which are respectively detachably fitted in the upper ends of the vertical tubes 1, 2. The said emery wheels are revoluble grinding elements, buffers, brushes, or the like, and are 55 on opposite ends of the shaft 23 of a motor 24, which is preferably an electric motor but may be a motor of any suitable type and which is secured on the upper side of the stand as shown. The said motor shaft 60 also has a pulley 25 which is connected by an endless belt 26, to a pulley 27 on the shaft 28 of the suction fan and hence the motor which drives the emery wheels, 65 brushes or other revoluble grinding, buffering or cleaning elements, also serves to drive the suction fan as will be understood.

A valve 28 is pivotally mounted as at 70 in the conduit 10 and may be turned to close either the arm 9 or the arm 6 and thus permit the suction fan to suck air from either 75 the hood 17 or the hood 18, as will be understood.

Dust and the like material may thus be sucked by the exhausted current in air from 80 either of the grinding, polishing, cleaning, or buffing elements. The light dust and lighter particles pass through the conduit 10 into the fan casing and drop from the latter through its arm 15 into the bag 16. 85 Such heavy particles as may enter the upper end of either of the tubes 1, 2, will drop directly down through said tube and be caught in the trap vessel 3 or 4, as the case may be.

In the form of the invention shown in 90 Fig. 4, in which the same is especially adapted for use on a dental table 80, there is only one vertical tube 37, provided at its lower end with a detachable trap closure 38 and 95 provided, at the upper end with a hood 39 that serves to throw the dust down in the vertical suction pipe. The horizontal conduit is indicated at 40 discharging into the exhaust fan casing 41, and the vertical arm 110 42 of said pipe is closed by a cap 43. The valve 44 is normally held in open position.

The motor is indicated at 45. It will be understood that this form of the dust collector can be provided by merely detaching the tube 1 and elbow 7, from the pipe 10, 5 and hence the dust collector may be arranged for use in connection with either two or one grinding, polishing, buffing, or cleaning elements as may be desired.

The suction fan 12 is provided with blades 10 46 at the outer ends of spoke arms 47 which project radially from the shaft 28, and each blade is provided at its front end with an inturned and inwardly extending suction arm 48. The casing 11 is provided with 15 bearings 49, 50, for the fan shaft, the bearing 50 being at the end of a bracket arm 51. The front side of the fan casing is provided with radial lugs 52 which may be bolted to the flange 53 at the outer end of the conduit 20 10 or the conduit 40, as the case may be.

To enable the fan casing to be attached directly to the stand instead of to the suction conduit, the form of the fan casing 11, shown in Fig. 7 is provided with feet 54, 25 which may be screwed or bolted to the stand.

From the foregoing description, taken in connection with the accompanying drawings, the advantages of construction and of the method of operation will be readily apparent to those skilled in the art to which the 30 invention relates, and while I have described

the principles of operation of the device together with the device which I now consider to be the best embodiment thereof, I desire to have it understood that the device 35 shown is merely illustrative and that such changes may be made when desired as are within the scope of the claim appended hereto.

Having described the invention, what is 40 claimed is:

A dust collector of the class described, comprising a pair of vertical tubes each having an elbow at a point intermediate its ends, a dust trap at the lower end of each 45 of said tubes, a conduit detachably connected at one end to the elbow of one of said tubes, said conduit having an arm at a point intermediate its ends and being also provided with a valve to close across said conduit or 50 said arm at will, a suction fan having a casing directly connected to the other end of said conduit and into which the latter discharges, a dust collecting receptacle connected to and carried by the fan casing and into 55 which the latter discharges, and a second conduit detachably fitted at one end to the elbow of the other vertical tube and having an elbow at the opposite end connected to the arm of the first-named conduit. 60

In testimony whereof I affix my signature.
HARLEN L. BEE.
